UNITED STATES PATENT OFFICE.

ETTA BELCHER, OF PROVIDENCE, RHODE ISLAND.

DESIGN FOR A BUBBLE-BLOWER.

SPECIFICATION forming part of Design No. 20,050, dated July 22, 1890.

Application filed April 25, 1890. Serial No. 349,504. Term of patent 7 years.

To all whom it may concern:

Be it known that I, ETTA BELCHER, a citizen of the United States, residing at Providence, in the county of Providence and State 5 of Rhode Island, have invented and produced a new and original Design for Bubble-Blowers, of which the following is a specification, reference being had to the accompanying drawing, forming part thereof.

10 The drawing is a side view of a bubble-blower showing my design. The broken lines indicate the interior configuration of the bubble-blower.

15 The leading feature of my design consists in the outline and configuration of the bowl of the bubble-blower, representing a human head with open mouth and the appearance of blowing.

A designates a tubular stem connecting

with the bowl B at a point opposite to the 20 opening C, representing the mouth.

d indicates the chin, E the nose, and f the forehead.

The general outline of the bowl is the outline of a more or less grotesque human head 25 having an exaggerated open mouth and the general expression of blowing a soap-bubble.

What I claim is—

The design for a bubble-blower herein shown and described, the same consisting in 30 a bowl having the outline and configuration of a human head, and the mouth surrounding the open end of the bowl, with a stem projecting from the head, as set forth.

ETTA BELCHER.
